CLAIM

The ornamental design for a water flotation suit, as shown and described herein.

DESCRIPTION

FIG. 1 is a front elevation view of a water flotation suit according to a first embodiment of the present disclosure; FIG. 2 is a rear elevation view thereof;

FIG. 3 is a left side elevation view thereof;

FIG. 4 is a right side elevation view thereof;

FIG. 5 is a top plan view thereof; and,

FIG. 6 is a bottom plan view thereof.

A second embodiment of a water flotation suit according to the present disclosure is a mirror image of the water flotation suit shown in the first embodiment.

The broken lines shown are included for the purpose of illustrating portions of the water flotation suit that form no part of the claimed design.

1 Claim, 4 Drawing Sheets(56)
